SPRAY DISPENSER

Benson C. Brainard, St. Paul, and Leo F. Wildgen, Minneapolis, Minn., assignors to Lavoptik Company, St. Paul, Minn., a corporation of Minnesota

Filed Feb. 5, 1962, Ser. No. 68,669

Term of patent 14 years

(Cl. D58—17)

FIG. 1

FIG. 3

FIG. 2

FIG. 4

FIG. 5

FIG. 7

FIG. 6

FIGURE 1 is a front elevational view of a spray dispenser in closed position, showing our new design;

FIGURE 2 is a side elevational view of the same;

FIGURE 3 is a top plan view of the same;

FIGURE 4 is a top plan view of the spray dispenser with the top closure in position for spraying;

FIGURE 5 is a side elevational view of the same in the position shown in FIGURE 4;

FIGURE 6 is a front elevational view of the same in the position shown in FIGURES 4 and 5, and

FIGURE 7 is a fragmentary front perspective view looking down on the top of the spray dispenser.

We claim:

The ornamental design for a spray dispenser, as shown.
